[57] CLAIM

The ornamental design for a fishing lure hook trailer, as shown and described.

DESCRIPTION

FIG. 1 is a top plan view of a fishing lure hook trailer showing my new design;

FIG. 2 is a side elevation view thereof, it being understood that the opposite side is a mirror image thereof;

FIG. 3 is a head end elevation view thereof;

FIG. 4 is a tail end elevation view thereof; and,

FIG. 5 is a bottom plan view of the fishing lure hook trailer.
